To all whom it may concern:

Be it known that I, ANNA K. MAY, a citizen of the United States, residing at the city of Philadelphia, in the county of Philadelphia and State of Pennsylvania, have invented and produced a new and original Design for a Carpet or other Fabric, of which the following is a specification, reference being had more particularly to the accompanying drawing, illustrating the same and forming part hereof.

The leading feature of my design is a Morris-style pattern of conventionalized leaves and flowers.

In the drawing, *a* is the body, *b* the border, and *a b* the complete carpet.

c are conventionalized leaves, and *d* are conventionalized flowers arranged, as shown, to present very little of the ground *e* to view and form a pattern, as shown, of the Morris style.

The design of my invention will be best understood by reference to the drawing, and it may be expressed in any desired colors or combinations of colors and applied to velvet, Wilton, Brussels, or other carpeting.
